(57) **CLAIM**

The ornamental design for a training device for balance, agility, and proprioception exercises, as shown and described.

DESCRIPTION

FIG. 1 is a top plan view of a training device for balance, agility, and proprioception exercises showing my new design. FIG. 2 is a bottom plan view thereof.

FIG. 3 is a front plan view thereof, each of the rear plan view, right side elevational view, and left side elevational view being a mirror image of the front plan view and therefore not illustrated; and,

FIG. 4 is a perspective view thereof.

The broken lines illustrate portions of the training device which form no part of the claimed design.
